UNITED STATES PATENT OFFICE.

WILLIAM A. KENDRICK, OF WASHINGTON, DISTRICT OF COLUMBIA, ASSIGNOR TO THE AMERICAN LAUNDRY MACHINERY COMPANY, OF NORWOOD, OHIO, A CORPORATION OF OHIO.

APRON CONTROL.

Application filed August 14, 1920. Serial No. 403,580.

This invention relates to a means for controlling the movement of a web or belt member, as for instance, an apron used in a flat work ironing machine, the idea being to correct the sidewise movement of the apron.

One object of the invention is to provide a means whereby the apron will be caused to maintain its proper path of travel through the machine so as to prevent it from creeping 10 to one side or the other of the machine.

Another object of the invention is to provide a means for correcting any sidewise displacement of the apron, which means will be automatically actuated by a slight creeping movement of the apron toward one side or 15 the other.

Another object is to effect a correction corresponding exactly with the degree of displacement of the apron.

20 A still further object of the invention is to provide a means at the edges of the apron, which, upon actuation by any sidewise movement of the apron, will cause the raising or lowering of one end of the rollers over which 25 the apron passes.

A still further object of the invention is to 30 provide an automatic adjustment means which will be actuated by any sidewise movement of the apron and thereby cause an adjustment of one end of one of the rollers toward or away from the apron and at the same time an adjustment of the other end of 35 the same roller in the opposite direction.

This invention might be embodied in other 40 forms of structure but the preferred form will be understood from the following description and claims considered together with the accompanying drawings.

Fig. 1 shows in elevation the front part of a 45 regular mangle type of flat work ironer and relative location of my apron control means; Fig. 2 shows in front elevation, several spools of a flat work ironer and relative location of my automatic control means; Fig. 3 shows partly in transverse section and partly in plan 50 view the relative arrangement of the apron control means; Fig. 4 shows a perspective of the apron control means mounted upon the bracket of the flat work ironer; Fig. 5 is a graphic representation of the adjustment of the roller; and Fig. 6 shows in sectional detail, a secondary adjustable connection between the journal bearing of the roller and the lever-mechanism.

In the operation of an apron belt or web 55 over a roller some difficulty has been experienced because of the creeping of the apron to one side or the other of the machine with the result that it would become entangled in the machinery and badly damaged. This would 60 necessitate the stopping of the machine and the repairing of the apron, with the consequent loss of considerable time. In order to prevent such loss of time as well as such damage, it has been customary in some plants 65 to employ a workman to watch the movement of the apron and to adjust one of the rollers about which it passes so as to correct any sidewise movement of the apron he might consider serious. By means of this automatic 70 control it is unnecessary to watch the movement of the apron, thereby doing away with the labor of a workman.

Fig. 1 shows in a general way the front part 75 of the regular mangle flat work ironer, the bracket being indicated by the reference numeral 1 and several of the rollers being shown at 2, 3, 4, 5 and 6. The work, after having passed through the ironing machine, is delivered over the roller 5 and is received upon 80 table 8 at which point it can be folded for delivery. The means for operating the machine is not shown in the present drawings since such operating means is old in the art.

The roller 4 with its journal bearing 12 is 85 capable of movement up and down the rod member 13 and can be clamped in fixed position upon the rod 13 by means of screw 14. This is the roller which has in the past in some plants been adjusted to different positions 90 up and down the rods 13 and 13' by loosening the screw 14 and then tightening the same after the roller has been raised or lowered as required by the movement of the apron. This is the same roller which is automatically adjusted in its journal bearings by 95 my control means up and down the supports 13 and 13', and the specific means for effecting such adjustment will now be described.

A lever mechanism extending from the 100 journal bearing member 12 across the front of the apron to the opposite journal bearing member 12' is actuated by means of fingers 17 and 17' which are adjustably mounted upon the angle bar 18, these finger members being 105 so located that they will follow the side edges of the apron as it tends to creep to one side or other of the machine. The fingers 17 and

17' may be given different positions along the angle bar 18 by means of spaced holes 19 and 19' according to the width of the apron. The angle bar 18 has pivotal connections at 21 and 21' with the bell crank levers 20 and 20' which are pivotally mounted at 22 and 22' upon the overhanging brackets 16 and 16'. The shorter arms of the levers mounted at 22 and 22' have pivotal engagement at 23 and 23' with the connecting bars 24 and 24', adjustment being allowed by means of the series of holes in the shorter arms of the lever members 20 and 20'. The connecting bars 24 and 24' have pivotal engagement at 25 and 25' 15 with the levers 26 and 26' which are pivotally mounted at 27 as upon the uprights 15 and 15' of the frame of the machine. The lever arms 26 and 26' are pivotally connected at 29 and 29' to connecting bars 28 and 28' which are secured at 30 to the journal bearing member 12, and in like manner to bearing 12', the last connection not being shown. Thus it will be seen that as the apron tends to creep from one side of the machine to the other it 20 will move against one or the other of the fingers 17 and 17', with the result that the bar 18 will be moved either to the right or to the left. It will also be seen that the movement of the bar 18 to the right will cause 25 the journal bearing member 12' to be lowered, while at the same time the journal bearing member 12 will be raised. The result of this adjustment will be that the apron will then move slightly in the opposite direction, that 30 is, toward the left side of the machine, sufficiently to bring it back to its normal path. Then, should the apron tend to move toward the left side of the machine, the edge of the apron contacting with the finger 17 will cause 35 the bar 18 to move toward the left, with the result that the journal bearing member 12 will be lowered and the bearing 12' raised, thereby preventing the apron from any further movement toward the left side of the 40 machine and in this way keeping it in its normal path. The fingers 17 and 17' are placed at a point near the roller 4, so that the degree of adjustment of this roller will represent exactly the degree of creeping movement of the apron.

In Fig. 2 it will be seen how the edge of the apron impinges against the finger member 17 with the edge portion of the apron folded back, as the result of such contact, 55 thereby effecting a successful actuation of the lever mechanism.

In Fig. 5 will be seen in graphic representation the adjustment of the roller member in its bearings, the one end of the roller being 60 raised while the other end is lowered. Of course, it is understood that the movement of the apron can be corrected by having one journal bearing of the roller clamped in fixed position upon its upright support and allowing only the other journal bearing member

to be adjusted, sufficient play being allowed in the fixed journal bearing member for such movement of the journal about the fixed bearing member as a pivot. There is also sufficient play between the journal bearings and 70 their supports to allow their adjustment thereon. Whether one or both of the journal bearings are adjusted, both of the finger members 17 and 17' would be employed so as to be able to correct the movement of the apron 75 in either direction across the machine. When only one bearing is adjusted, however, it will be seen that in order to effect a given difference of elevation between the two ends of the roller, it will be necessary to make the 80 entire adjustment at one end; whereas, if both journal bearing members are made adjustable, as indicated in Fig. 5, then it would be necessary to raise one end of the roller only half of the given distance since the other 85 end of the roller would at the same time be lowered half the given distance. With this arrangement, the adjustment has been found to be more quickly effected than in the other arrangement.

As shown in Fig. 1, the adjustable roller 4 is located in a bight of the apron and the direction of travel of the apron is indicated by arrow. The result of the adjustment of the roller in the manner above described is to 90 vary its angle with respect to the path of the apron; and the apron, due to a natural tendency will in the present case shift across the machine toward the higher end of the roller.

Of course it is to be understood that my invention might also be carried out by arranging the roller so as to be adjusted in other directions than that here shown, it not being absolutely necessary that the roller be adjusted in a vertical plane. It is to be understood also that my invention is not limited to use in an ironing machine but is capable of general application to all devices in which it is desirous to correct the movement of a traveling apron or the like.

By means of additional holes in the lever mechanism, as above referred to, several adjustments can be had with the result that for a certain movement of the apron to one side or the other, the journal bearing members will be raised more or less, according to the points of connection between the lever members. A finer adjustment is provided by the means shown in Figs. 1 and 6, which might be substituted for the connecting bars 28 and 28' at either one or the other end of the roller, or at both ends, as may be desired. As will be seen from Fig. 6, the clevis member 32 can be connected with the lever member 26 by means of the same bolt connection 29, and has screw thread engagement with the adjusting pin which terminates at its lower end in the manipulating head 37. 33 is a lock nut. The screw nut 34 is spaced from the bolt head 36 by means of the loosely mount- 115

ed block 35. The threads 38 of the screw bolt 36 have engagement with the journal bearing member 12 or 12'. Thus, it will be seen that by turning the threaded pin member at 5 its lower end 37, the lever connection between the points 29 and 38 can be shortened or lengthened to as fine a degree as desired. The idea of the adjusting means is to set the roller 4 in a horizontal plane at the beginning of the 10 operation. If such positioning of the roller cannot be had by adjustment of the bolt 25 in the series of holes shown in the lever arm 26, then the finer adjusting means, as illustrated in Figs. 1 and 6, will be resorted to.

15 As shown in Fig. 1, the roller 3 is the one used for tightening the apron by means of rack and pinion connection 9 and 10, the wheel for manipulation of the rack and pinion being indicated at 11.

20 Among the advantages resulting from the use of this device is the automatic correction of the movement of the apron or web member across the machine, without the necessity of constantly observing its action. Another advantage consists in the adjustable connections provided in the lever mechanism by means of which as fine an adjustment as desired can be effected. The adjusting mechanism is very simple, while at the same time the proper correction is assured. Furthermore, the adjustment is accomplished in a very short interval of time and as a result the movement of the apron from side to side is reduced to a minimum.

35 Other advantages resulting from this invention will suggest themselves to those who are familiar with the art.

What I claim is:

1. In an apron control mechanism, the combination of a roller over which an apron is adapted to travel, said roller having a journal bearing adjustable up and down to allow movement of said roller angularly with

respect to said apron, and means controlled by transverse movement of said apron at said 45 roller for automatically effecting adjustment of said roller journal bearing, said means consisting of lever arms upon which is suspended said roller journal bearing.

2. In an apron control mechanism, the combination of a roller over which an apron is adapted to travel, said roller having an adjustable journal bearing to allow movement of said roller angularly with respect to said apron, movable fingers arranged at the edges 55 of said apron and adapted to be actuated by transverse movement of said apron, and balanced lever mechanism operatively connected with said fingers and from which is suspended said roller journal bearing for automatically effecting adjustment of said roller journal bearing.

3. In an apron control mechanism, the combination of a roller over which an apron is adapted to travel, said roller having an adjustable journal bearing to allow movement of said roller relative to said apron, and means controlled by transverse movement of said apron for automatically effecting adjustment of said roller journal bearing, said 65 means including a lever arm upon which said roller journal bearing is suspended.

4. In an apron control mechanism, the combination of a roller over which an apron is adapted to travel, said roller having adjustable journal bearings to allow movement of said roller relative to said apron, and means controlled by transverse movement of said apron and adjacent said roller for automatically effecting adjustment of said journal 75 roller bearings, said means including lever arms upon which said roller journal bearings are suspended.

In testimony whereof I affix my signature.

WILLIAM A. KENDRICK.
